SPECIFICATION forming part of Design No. 22,087, dated December 27, 1892.

Application filed November 7, 1892. Serial No. 451,240. Term of patent 3½ years.

To all whom it may concern:

Be it known that I, WILLIAM F. PATTERSON, of Jersey City, in the county of Hudson and State of New Jersey, have invented and produced a new and original Design for Window-Shades and Wall-Paper, of which the following is a specification, reference being had to the accompanying drawing, forming a part thereof, which represents a plan view of the design.

The design consists of the representation of the conventional picture of the Landing of Co-
